Primary Examiner — Rhea Shields(74) *Attorney, Agent, or Firm* — McNees Wallace & Nurick LLC(57) **CLAIM**

The ornamental design for a catheter package, as shown and described.

DESCRIPTION

FIG. 1 is a perspective view of a catheter package, showing my new design.

FIG. 2 is a front plan view of the catheter package shown in FIG. 1;

FIG. 3 is a bottom plan view of the catheter package shown in FIG. 1;

FIG. 4 is a left side elevational view of the catheter package shown in FIG. 1;

FIG. 5 is a rear elevational view of the catheter package shown in FIG. 1;

FIG. 6 is a top plan view of the catheter package shown in FIG. 1; and,

FIG. 7 right side elevational view of the catheter package shown in FIG. 1.

1 Claim, 3 Drawing Sheets(56)
